UNITED STATES PATENT OFFICE.

JOHN CLAUDE ARMOUR, OF MONTREAL, QUEBEC, CANADA.

PORTABLE ELECTRIC LAMP.

Application filed May 31, 1922. Serial No. 564,973.

To all whom it may concern:

Be it known that I, JOHN CLAUDE ARMOUR, a subject of the King of Great Britain, and residing at the city of Montreal, in the Province of Quebec, in the Dominion of Canada, have invented a new and useful Portable Electric Lamp, of which the following is the specification.

The invention relates to portable electric lamps as described in the present specification and illustrated in the accompanying drawings that form part of the same.

The invention consists essentially of the novel features of construction pointed out broadly and specifically in the claim for novelty following a description in detail of the preferred form of the invention.

The objects of the invention are to furnish to the public in the one article a hand-some desk or table lamp and a reliable clamping lamp adapted to grip securely a table, shelf or other board or frame; to reduce the cost of construction; to insure a permanent and unobstructed passage for the electric cord; to eliminate the pivoted arms common to clamping lamps; and generally to provide a durable and efficient lamp at a comparatively low cost.

In the drawings, Figure 1 is an elevation of the lamp.

Figure 2 is a vertical sectional view showing the clamping plate closed on the base.

Figure 3 is a vertical sectional view showing the clamping plate and base gripping a table.

Figure 4 is a detail of the cap of the clamping plate stem.

Figure 5 is a detail of the clamping plate stem.

Figure 6 is a detail of the fillet ring.

Figure 7 is a detail of the stem thimble.

Figure 8 is a detail of the clamping plate.

Like numerals of reference indicate corresponding parts in the various figures.

Referring to the drawings, the permanent base 1 is preferably formed with the curled out bottom 2 and dished centre 3 having the post hole 4.

The lamp post 5 is tubular and externally threaded at the upper end 7, said lower end projecting through the hole 4 and securely fastened by the nuts 8 and 9.

Intermediate of the height of the post 5 the pin 10 projects from the wall at each side and holds the washer 11 down on the spiral ring 12, which encircles said post.

The upper side of the base 1 is perfectly flat surrounding the dished centre 3 and is covered by the felt 13.

The clamping plate 14 is also formed with a flat felt covered bottom 14^a, corresponding to the felt top 13 of the base which cooperates with the clamping plate 14 in holding the lamp to a table, frame or shelf.

The clamping plate stem 15 is externally threaded at the upper end 16 and internally threaded at the lower end 17 and screws on to the thimble 18, which is flanged under the clamping plate 14 and projects therethrough forming a stop for the spiral spring 12, the joint of the stem 15 and plate 14 being hidden by the fillet ring 19.

The cap 20 is screwed on to the upper end of the stem 15.

The lamp bracket 21 is suitably secured to the top of the post 5 and the lamp socket 22 is pivotally attached thereto, but this part has nothing to do with the invention other than being part of a regular lamp construction.

In clamping the lamp to a table or shelf the stem 15 is grasped by the hand of the person and pulled upwardly thereby lifting the plate 14 away from the base 1 and at the same time compressing the spring 12 so that when the person lets go the plate 14 is sprung downwardly on the table between the base and clamping plate and coincidentally the base is pulled upwardly by the spring, which insures a fast hold on the object to which the lamp is attached.

What I claim is:

A portable electric lamp comprising a base and a central post adapted together to form a permanent cord receptacle and passage leading from a cord inlet in the base wall to a cord outlet to the lamp at the top of said post, a spring stop intermediate of the height of said post, a spring around the outer surface of said post under said stop, a clamping plate normally spring-held to said base and encircling said post, and a hollow stem projecting upwardly from and rigidly secured to said plate and enclosing said spring and compressing the same against said stop on the operation of said stem.

Signed at Montreal, Canada, this 22 day of May, 1922.

JOHN CLAUDE ARMOUR.
